Letters Patent No. 250. dated November 13th 1849.
The schedule referred to in these letters Patent and
making part of the same -

NOTICE OF INVENTION

To all whom it may concern: Be it known that Samuel Clark of Troy in the County of Rensselaer, and State of New York, have invented or produced a new design of Parlor Stove plates, which I call the Commercial parlor No. 3, and I do hereby declare that the following is a full clear and exact description of the same, reference being had to the annexed drawings making a part of this specification in which Fig. 1. is a view of the front, and Fig. 2. of the end plates of the stove.

In the drawings I have represented only part of the ornaments, the remainder being a repetition of, and corresponding with that represented on the other parts.

2
of the plates as is plainly to be seen by reference to the
drawing of
what I claim as new and desire to secure by letters
patent is the design and configurations of ornamental
stone plates, as herein described and represented in the
accompanying drawings.
